CLAIM

The ornamental design for a round bubble machine as shown and described.

DESCRIPTION

FIG. 1 is a top, front and right side perspective view of a round bubble machine showing the claimed design;

FIG. 2 is a bottom, rear and left side perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is a perspective view of the round bubble machine shown in an open state; and,

FIG. 10 is an enlarged view of the portion 10 shown in FIG. 1.

The dash-dash broken lines depict portions of the round bubble machine including the entire bubble wheel portion shown in FIGS. 1, 3 and 9, that form no part of the claimed design; the dash-dot-dash broken lines depict the boundaries of enlarged views and form no part of the claim design.

1 Claim, 10 Drawing Sheets
